UNITED STATES PATENT OFFICE.

FERDINAND NOETHLICH, OF UTE, IOWA.

DUMPING-CARRIAGE.

1,301,962.

Specification of Letters Patent. Patented Apr. 29, 1919.

Application filed October 25, 1918. Serial No. 259,730.

To all whom it may concern:

Be it known that I, FERDINAND NOETHLICH, a citizen of the United States of America, and resident of Ute, Monona county, 5 Iowa, have invented certain Improvements in Dumping-Carriages, of which the following is a specification.

The object of this invention is to provide an improved construction for a carriage 10 adapted to receive, convey and deposit material such as earth from an excavation.

A further object of this invention is to provide an improved construction for means 15 to retain a dumping-bottom in closed position so as to retain and convey material in a carriage.

A further object of this invention is to provide improved means for opening or releasing a dumping-bottom in a carriage, said 20 means being adapted for manual actuation or for tripping operation by means carried by a track over which the carriage travels.

A further object of this invention is to provide improved means for setting or adjusting the bottom to closed position and setting the retaining devices relative thereto.

A further object of this invention is to provide improved means for preventing leakage of material, such as earth, from the 30 bottom of a dumping carriage.

A further object of this invention is to provide improved means for locking the steering-truck of a dumping carriage for travel of said carriage on a track in a right 35 line.

My invention consists in the construction, arrangement and combination of elements hereinafter set forth, pointed out in my 40 claims and illustrated by the accompanying drawing, in which—

Figure 1 is a plan, Fig. 2 a bottom plan, Fig. 3 a side elevation and Fig. 4 a rear end elevation of a carriage embodying my invention, the wheels being omitted from Figs. 1, 45 2 and 4. Fig. 5 is a detail side elevation of the rear portion of the carriage, the dumping devices and bottom being shown in open or dumped position. Fig. 6 is a cross-section on an enlarged scale, on the indicated line 50 6—6 of Fig. 2. Fig. 7 is a detail plan of a tongue or bail adapted to be employed on drawing the carriage.

The device herein shown and described 55 may be employed in connection with the elevating mechanism illustrated, described and claimed in my companion application filed

October 25, 1918, Serial Number 259,729; although its use is not limited to such associated use.

In the construction of the device as shown 60 a box is employed, comprising side walls 10, 11, end walls 12, 13, and a center-bar 14 rigidly connected, the bottom face of the center-bar being flush with the lower margins of the side-walls; together with dumping leaves 65 or boards 15, 16 fitted between said walls and center-bar and hinged to the side walls, thus forming a bottom for the box. Aprons 17, 18 are fixed to the side and end walls respectively and a triangular apron 19 is fixed to 70 the center-bar, said aprons preferably being made of sheet metal and arranged to overlap the joints or cracks formed by the margins of the bottom boards or leaves 15, 16 to prevent leakage of material from the box. 75 Arms 20, 21 are fixed to the bottom faces of the boards or leaves 15, 16 and extend across and at right angles to the inner margins of said boards in overlapping relation with the center-bar 14. A groove is formed in and 80 longitudinally of the bottom of the center-bar 14 and a locking-bar 22 is slidingly mounted in said groove, and is confined therein by clips 24 laid across the locking-bar and fixed to the center-bar. Plates 25 85 are fixed to the locking-bar 22 and project laterally therefrom and are adapted to overlap and confine the inner ends of the arms 20, 21 and hold the leaves or boards 15, 16 in closed position (Fig. 6). An anchor 26 is 90 fixed at one end to the forward portion of the bottom of the box and inclines downwardly and rearwardly therefrom and a retractile coil spring 27 is attached at one end to the lower rear end of said anchor, extends 95 across the forward clips 24 and plate 25 and is attached at its rear end to the locking-bar 22. It is the function of the spring 27 to draw and hold the locking-bar 22 forwardly with the plates 25 in positions to lock the 100 arms 20, 21 and boards 15, 16 in closed positions. The locking-bar 22 is turned downwardly at its rear end to form a hook or handle 28 adapted for manual engagement to move the locking-bar rearwardly against 105 the pull of the spring 27 to release the arms 20, 21 from the plates 25 and permit the leaves or boards 15, 16 to fall into open positions (Fig. 5). The hook or handle 28 also is adapted to engage a stop (as shown in my 110 companion application above referred to) and, in the further travel of the carriage,

effect the same relative movement of the locking-bar. An angle plate 29 is fixed to and projects upwardly from the rear end portion of the locking-bar 22, opposite the 5 hook or handle 28, and the upwardly-projecting portion of said plate inclines rearwardly. A lever 30 is fulcrumed between its ends on the rear end portion of the carriage and an expansive coil spring 31 is interposed between the upper portion of said 10 lever and the rear end wall 13 of the box and tends to hold the lever in a given position. The lower end of the lever 30 is adapted to pass over and engage the angle 15 plate 29 when the locking-bar 22 is moved rearwardly to opening position and hold said locking-bar during the dumping operation. Lifting arms 32, 33 are fixed to and extend rearwardly from the leaves or boards 20 15, 16 adjacent to the center-bar 14 and a closing lever or handle 34 is fulcrumed at one end to a bracket 35 fixed to and extending rearwardly from the upper portion of the rear wall 13 of the box and inclines down- 25 wardly and rearwardly from said bracket. Chains 36, 37 are fixed to central portions of the lever 34 at one end and the opposite ends of said chains are attached by coil springs 38, 39 to rear ends of the lifting 30 arms 32, 33. A hook 40 is formed on the upper end of the lever 30 and extends across the bracket 35 and said hook is adapted to be engaged by the closing lever 34 at times to oscillate the lever 30 and release the en- 35 gagement thereof with the angle plate 29 so that the locking-bar 22 may be returned to closing position by the spring 27. Bolsters or sand-boards 41, 42 are fixed to and extend across and beneath the box at the front and 40 rear ends thereof respectively, and arcuate bars 43, 44 are fixed at their inner upper ends to the bolster 42 and curve downwardly and laterally in opposite manner therefrom and terminate in hooks 45. The lifting arms 32, 45 33 are offset between their ends to clear the bolster 42 and said arms are adapted to move through arcs to and from open and closed positions with their offset portions in contact, slidingly, with the arcuate bars 43, 50 44. The lifting arms are adapted to engage and be stopped in open position by the hooks 45 on the arcuate bars. An axle 46 is pivoted by a king-bolt 47 to the bolster 41 and is provided with wheels 48, one of which is 55 shown in Fig. 3. A hook 49 is pivoted at its rear end to the side wall 11 of the box and is adapted to engage at times with an eye 50 projecting rearwardly from one end portion of the axle 46; said hook being adapted to 60 engage at times and be held in inoperative position by an eye 51 on said wall. When in the first position the hook 49 locks the axle 46 against rotation on the king-bolt 47 and holds the carriage to a straight or right 65 line of travel, as is indicated when said car-

riage is used on a structure such as is defined in my companion application. The rear bolster 42 is provided with an axle 52 fixed thereto and furnished with wheels 53, one of which is shown in Fig. 3. A handle, 70 tongue or bail 54 is pivoted to the axle 46 and is adapted to be attached to draft means, such as the cable shown in my companion application, for drawing the carriage as de- 75 sired.

In practical use the leaves or boards 15, 16 are locked in closed position and the box is loaded with material and drawn to a place of deposit of such material. The hook 28, preferably, is caused to engage a stop so located and arranged as to hold the locking-bar 22 while the carriage travels a sufficient distance to release the arms 20, 21 from the plates 25, whereupon the lever 30 passes over and engages the angle plate 29 to prevent 85 accidental return of the locking-bar to locking position and the leaves or boards 15, 16 fall to open position and are limited in such movement by engagement of the arms 32, 33 with the hooks 45. The carriage then is 90 stopped, such as by engagement with extra- neous elements as defined in my companion application; the dumping leaves or boards 15, 16 are raised by manually moving the lifting lever 34 upwardly through an arc, 95 thus applying lifting force to the arms 32, 33 through the chains 36, 37 and springs 38, 39, said springs applying yielding strain; and, when the lever 34 reaches an upright position it is moved forwardly and contacts with 100 and moves forwardly the upper end of the lever 30, thus causing the lower end of said lever to release the angle plate 29 and permit the locking-bar 22 to be moved forwardly by the spring 27 and place the plates 105 25 beneath and in retaining relations with the arms 20, 21. Then the lever 34 is per- mitted to fall into inoperative position, the lever 30 reassuming a position to engage the angle plate 29 on the next dumping opera- 110 tion of the carriage.

I do not desire to be limited to the precise construction and arrangement of parts, as the same may be altered in many particulars within the scope of the appended claims with- 115 out departing from my invention.

I claim as my invention—

1. A dumping carriage, comprising a box having a bottom formed with leaves hinged at their sides and opening from the center, 120 a locking-bar mounted for reciprocation in the center of said bottom and adapted to be spring-drawn in one direction and automatically stop-operated in the opposite di- 125 rection through forward movement of said carriage, arms on said leaves, plates on said locking-bar adapted to engage said arms at times, trucks supporting said box and means for drawing said trucks.

2. A dumping carriage, comprising a box 130

- having a bottom formed with leaves hinged to the sides and opening from the center of the box, a center-bar being mounted in said box and separating said leaves, a locking-bar mounted for reciprocation in said center-bar and spring-drawn in one direction, a hook being formed on the opposite end of said locking-bar adapted to engage a fixed stop for movement in the opposite direction, 5 a trigger adapted to engage said locking-bar, and closing means adapted for manual actuation to raise said leaves and trip said trigger.
3. A dumping carriage, comprising a box 15 having a bottom formed with leaves hinged to the sides and opening from the center of the box, a center-bar being mounted in said box and separating said leaves, a locking-bar mounted for reciprocation in said center-bar, arms on said leaves overlapping said center-bar, plates on said locking-bar adapted to overlap said arms, a spring adapted to move said locking-bar into locking position, the opposite end of said locking-bar being 20 formed to engage a stop, in the travel of the carriage, and move said locking-bar against the pressure of said spring, lifting arms extending rearwardly from said leaves, a lever fulcrumed on the rear wall of the box, and 25 flexible connections between said lever and lifting arms.
4. A dumping carriage, comprising a box having a bottom formed with hinged leaves, means for locking said leaves in closed position, means for releasing and holding the locking means in open position, which holding means comprises a spring-held lever, lifting arms fixed to said leaves, a lever fulcrumed on the rear wall of the box, flexible 30 connections between said lever and lifting arms, said connections including springs, and trucks for said box.
5. A dumping carriage, comprising a box having a bottom formed with leaves hinged 35 to the sides and opening from the center of
- the box, a center-bar being mounted in said box and separating said leaves, means for locking said leaves in closed position, means for releasing and holding the locking means in open position, which holding means comprises a spring-held lever, lifting arms fixed to said leaves, a lever fulcrumed on the box, flexible connections between the lifting arms and lifting lever, which connections include springs, and trucks for said box, said lifting lever being adapted to engage and operate the spring-held holding lever at times. 50
6. A dumping carriage, comprising a box having a bottom formed with leaves hinged to the sides and opening from the center of the box, a center-bar being mounted in said box and separating said leaves, means for locking said leaves in closed position, means for releasing the locking means, a lever fulcrumed on the box and adapted to hold the released locking means in open position, which lever is spring-held in one direction, lifting arms fixed to said leaves, a lifting lever fulcrumed on the box, flexible connections between the lifting arms and lifting lever, which connections include springs, said lifting lever being adapted to engage and operate the holding lever at times, and trucks for said box. 55
7. In a dumping carriage, a box, leaves hinged at their outer margins and forming a dumping bottom for said box, arcuate bars fixed at one end to said box and curving downwardly and laterally in opposite directions, said bars being formed with terminal hooks, lifting arms fixed to, projecting from and offset away from said leaves, said arms being adapted for sliding engagement with said bars when the leaves move to open 60 position and also adapted to be stopped by engagement with said terminal hooks, and means connected with said lifting bars for returning said leaves to closing position. 70
- FERDINAND NOETHLICH. 75
